US00D732548S

(12) **United States Design Patent**
Lee et al.

(10) **Patent No.:** US D732,548 S
(45) **Date of Patent:** ** Jun. 23, 2015

(54) **KEYBOARD**

(71) Applicant: **Samsung Electronics Co., Ltd.**, Suwon-Si (KR)

(72) Inventors: **Jooyeon Lee**, Gunposi (KR); **Kyu Eun Hwang**, Seoul (KR); **Whan Oh Sung**, Seoul (KR); **Youngkeun Lee**, Seoul (KR); **Jochen Backs**, San Francisco, CA (US)

(73) Assignee: **Samsung Electronics Co., Ltd.**, Suwon-si (KR)

(**) Term: **14 Years**

(21) Appl. No.: **29/466,183**

(22) Filed: **Sep. 5, 2013**

(30) **Foreign Application Priority Data**

Mar. 5, 2013 (KR) 30-2013-0011221

(51) **LOC (10) Cl.** **14-02**

(52) **U.S. Cl.**

USPC **D14/455**

(58) **Field of Classification Search**

USPC ..... D14/315-327, 331; D18/1, 2, 7, 11; 235/145 A, 145 R; 341/22, 23; 345/104, 345/156, 168, 169, 173; 361/679.06, 361/679.08, 679.09, 679.11, 679.26, 361/679.27; 379/433.12, 433.13; D5/47

(57) **CLAIM**

We claim the ornamental design for a keyboard, as shown and described.

DESCRIPTION

FIG. 1 is a front perspective view of a keyboard showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another perspective view in which a notebook computer is provided to illustrate and example environment; and, FIG. 9 is an exploded view thereof shown with the keyboard being rotated to the left.

The broken lines are for environmental purposes only and form no part of the claimed design.
